UNITED STATES PATENT OFFICE.

WILLIAM CARTER, OF LOUISVILLE, KENTUCKY.

FISHING-REEL.

SPECIFICATION forming part of Letters Patent No. 764,348, dated July 5, 1904.

Application filed January 21, 1904. Serial No. 189,996. (No model.)

To all whom it may concern:

Be it known that I, WILLIAM CARTER, a citizen of the United States, residing at Louisville, in the county of Jefferson and State of Kentucky, have invented new and useful Improvements in Fishing-Reels, of which the following is a specification.

This invention relates to certain new and useful improvements in fishing-reels, and aims particularly to provide new and novel means, hereinafter more specifically described, for fixedly retaining within the reel-frame the bearings for the front end of the spool and multiplying-gear.

The invention further aims to provide a fishing-reel with new and novel means, hereinafter more specifically described, for fixedly retaining within the reel-frame a head-plate carrying the bearing for the front end of the spool and the multiplying-gear.

The invention further aims to provide a fishing-reel with new and novel means, hereinafter more specifically described, for preventing the rotation of the head-plate carrying the bearing for the front end of the spool and the multiplying-gear and to further prevent the rotation of the cap for the front end of the spool.

The invention further aims to provide a fishing-reel which is so constructed as to permit, when occasion requires, of the removal of the spool, as well as other parts which go to make up the reel, and to also permit of the ready assembling of the parts when separated.

The invention further aims to construct a fishing-reel which shall be simple in its construction, strong, durable, efficient in its use, and comparatively inexpensive to manufacture.

With the foregoing and other objects in view the invention consists in the novel combination and arrangements of parts hereinafter more specifically described, illustrated in the accompanying drawings, and particularly pointed out in the claims hereunto appended.

In describing the invention in detail reference is had to the accompanying drawings, forming a part of this specification, wherein like reference characters denote correspond-

ing parts throughout the several views, and in which—

Figure 1 is a longitudinal section of the reel. Fig. 2 is a detail perspective view of the reel-frame. Fig. 3 is a perspective view of the head-plate carrying the bearings for the front end of the spool and the multiplying-gear. Fig. 4 is an elevation of the front cap, and Fig. 5 is an elevation of the closure-plate for the rear end of the frame.

Referring to the drawings by reference characters, 1 denotes the reel-frame constructed from a short tube of suitable material, said tube being cut away in such a manner as to form a pair of end bands 2, 3, a plurality of connecting-bars 4, and a connecting-bar 5 of greater width than the bars 4, and to said connecting-bar 5 is suitably connected the reel-seat 6. The end band 2 of the reel-frame 1 is of greater width than the band 3, and that end of the reel-frame 1 on which is arranged the band 2 is termed the "front" end of the fishing-reel. Although, as shown, the band 2 is of greater width than the band 3, yet said bands may be of the same width; but preferably the band 2 is constructed of greater width than the band 3.

The inner face of the band 2 is suitably bored away so as to form a shoulder or seat thereon near the inner end thereof. The inner face of the band 2 is also provided with screw-threads 8. These threads extend on the inner face of the band 2 from a point slightly removed from the shoulder or seat 7 to the outer end of the band.

The reference character 9 denotes a notch which is formed in the outer edge of the band 2, and the functions of said notch 9 and arranging the threads 8 will be hereinafter referred to.

Mounted within the band 2 and arranged against the shoulder or seat 7 is the front head-plate 10 of the reel, and said plate 10 has its edge bearing against the smooth inner face of the band 2—that is, that portion of the inner face of the band 2 which lies between the inner end of the threads 8 and the shoulder or seat 7. The plate 10 obtains a much better bearing against the smooth inner face of the band 2 than it would against the threads on

the inner face of the band, and consequently this is the reason that the inner face of the band 2 is not interiorly screw-threaded from the shoulder or seat 7 to the outer edge of the band.

5 The plate 10 is fixedly secured within the band 2 through the medium of an externally-screw-threaded fastening-collar 11, which is adapted to engage the threads 8 of the band 2 and to be screwed up snugly against the plate 10. The fastening-collar 11 is of such width that it does not extend to the outer edge of the band 2 and preferably is of such width as to extend to the bottom of the notch 9.

15 The head-plate 10 is provided centrally with an opening 12, and on the outer face of said plate 10 is arranged a housing 13, which surrounds the opening 12 and is formed integral with or otherwise connected to the plate 10. 20 The housing 13 is cut away at one side, as at 14, and the outer end of the housing 13 has a recessed protuberance 15 formed integral therewith or otherwise connected thereto. The protuberance 15 is of smaller diameter 25 than the housing 13, is cut away on one side, as at 16, to permit of setting the multiplying-gear, and is also screw-threaded, as at 17, for securing in position an attaching means to be hereinafter referred to. Through the opening 12, as well as the housing 13, extends the front end of the spindle 18 of the spool 19, and the said front end of the spindle 18 finds a bearing in the recessed protuberance 15. The pinion 20 upon the front end of the spindle 18 extends through the opening 12 and is surrounded by the housing 13. The plate 10 also has fixedly connected thereto the bearing-spindle 21 for the multiplying-gear 22, said gear being adapted to mesh with the pinion 20, and 40 such meshing is obtained owing to the cut-away portion 14 of the cap 13. The plate 10 is also provided with a shouldered fastening-stud 23, the function of which will be herein-after referred to.

45 The reference character 24 denotes the cap for closing the front end of the reel, and said cap consists of a circular plate having an annular depending flange 25, adapted to extend over the band 2. The cap 24 carries the multiplying-gear 22, to which is connected the handle 26. The cap 24 is provided with a centrally-arranged opening 27 and an opening 28, arranged near the edge thereof and further provided on its inner face with a stop-lug 29. 50 Through the opening 27 is adapted to extend the protuberance 15, and in the opening 28 is adapted to be seated the outer end of the shouldered stud 23, and the stop-lug 29 is adapted to be seated in the notch 9.

55 The reference character 30 denotes a fastening screw-nut mounted upon the extending end of the protuberance 15 for securing the cap to the front end of the reel-frame. The function of the stud 23 when the cap 24 is 60 secured in position is to prevent the rota-

tion of the plate 10, and the function of the stop-lug 29 when the cap 24 is secured in position is to arrest any movement of the cap 24.

70 The end band 3 is internally screw-threaded, as at 31, and said screw-threads 31 are adapted to be engaged by the externally-screw-threaded flange 32 extending into the band 3 and carried by the closure-plate 33 for the rear end of the reel-frame. The closure-plate 33 is provided with the bearing 34 for the rear 75 end of the spindle 18 of the spool 19. The closure-plate 34 carries a drag mechanism 35 and a click mechanism 36, and the rear end of the spindle 18 carries the pinion 37, which is adapted to be engaged by the click mechanism. 80

From the foregoing construction it is evident that a fishing-reel is devised by which the bearings for the front end of the spool and the multiplying-gear are fixedly retained within the reel-frame, and, furthermore, that the head-plate which carries said bearings is prevented from rotating, as well as the cap for the front end of the frame. Furthermore, a reel is set up which can be readily taken apart and assembled, and it is thought the many advantages of a fishing-reel constructed in accordance with the foregoing description can be readily understood, and it will furthermore be evident that changes, variations, and modifications can be resorted to without departing 90 from the spirit of the invention or sacrificing any of its advantages, and I therefore do not wish to restrict myself to the details of construction hereinbefore described and as shown in the accompanying drawings, but reserve 95 the right to make such changes, variations, and modifications as come properly within the scope of the protection prayed.

Having thus fully described my invention, what I claim as new, and desire to secure by Letters Patent, is—

1. A fishing-reel comprising a tubular reel-frame provided with an end band having its inner face provided with screw-threads and a shoulder and that portion of its inner face between the shoulder and screw-threads smooth, a head-plate mounted in said band against the smooth inner face thereof and against said shoulder, and a screw-threaded collar engaging the threads of the band for fixedly securing the plate in position.

2. A fishing-reel comprising a tubular reel-frame provided with an interiorly-screw-threaded end band, a head-plate mounted in said band and carrying bearings for the front end of the reel-spool and multiplying-gear, and a screw-threaded collar engaging the threads of the band for fixedly securing the plate in position.

3. A fishing-reel comprising a tubular reel-frame having a pair of end bands, one of which is interiorly screw-threaded and further provided with a shoulder at a point removed from the inner end of the screw-threads.

4. A fishing-reel comprising a tubular reel-

frame having a pair of end bands, one of which is internally screw-threaded and further provided with a shoulder at a point removed from its screw-threads, a plate within the band and 5 engaging the inner face thereof between the shoulder and the screw-threads, a screw-collar engaging the screw-threads of the band for retaining the plate within the band, and means engaging with the plate to prevent the 10 movement thereof.

5. A fishing-reel comprising a reel-frame having an end band, said band provided with a shoulder on its inner face and having its inner face further provided with screw-threads 15 extending at a point removed from said shoulder to the outer edge of the band.

6. A fishing-reel comprising a reel-frame having an end band, said band provided with a shoulder on its inner face and having its 20 inner face further provided with screw-threads extending at a point removed from said shoulder to the upper edge of the band, said band further provided with a notch in its outer edge.

25 7. A fishing-reel comprising a reel-frame having a pair of internally-screw-threaded end bands, one of said bands provided on its inner face with a shoulder at a point removed from its screw-threads.

30 8. A fishing-reel comprising a tubular frame having an end band, said end band provided on its inner face with screw-threads and a shoulder, a bearing-supporting plate mounted in said band against said shoulder, and means 35 engaging the threads of said band for fixedly securing the plate in position.

9. A fishing-reel comprising a tubular frame having an end band, said band provided on its inner face with screw-threads and a shoulder, 40 a bearing-supporting plate mounted in said band against said shoulder, means engaging the threads of said band and with said plate to prevent the movement of the latter, and an externally-screw-threaded collar engaging the 45 threads of said band for retaining the plate within the band.

10. A fishing-reel comprising a reel-frame provided with front and rear screw-threaded end bands, a bearing-supporting plate arranged 45 in said front band, means engaging the threads of the front band for fixedly securing said plate in position, a cap connected to said front end band for closing the front end of the reel, and a plate provided with an exteriorly- 55 screw-threaded flange adapted to engage with the threads of the rear end band for closing the rear end of the reel.

11. In a fishing-reel, the combination with a reel-frame, a reel-spool and a multiplying- 60 gear, of a head-plate mounted in one end of said frame and provided with a housing, a recessed protuberance, a shouldered stud, and a bearing for the multiplying-gear, said recessed protuberance forming a bearing for the front 65 end of the reel-spool.

12. In a fishing-reel, the combination with a reel-frame, a reel-spool and a multiplying-gear, of a head-plate mounted in one end of said frame and provided with a housing, a recessed protuberance, a shouldered stud, and a bearing 70 for the multiplying-gear, said recessed protuberance forming a bearing for the front end of the spool, said housing and protuberance cut away to permit of the setting and operation of the multiplying-gear. 75

13. In a fishing-reel, the combination with a reel-frame, a reel-spool and a multiplying-gear, of a head-plate mounted in one end of said frame and provided with a housing, a recessed protuberance, a shouldered stud and a bearing 80 for the multiplying-gear, said recessed protuberance forming a bearing for the front end of the spool, said housing and protuberance cut away to permit of the setting and operation of the multiplying-gear, a cap 85 inclosing said plate and provided with an opening adapted to receive the end of said stud to prevent the movement of the plate, and means mounted upon said protuberance for connecting said cap to the frame. 90

14. In a fishing-reel, the combination with a reel-frame, a reel-spool and a multiplying-gear, of a head-plate mounted in one end of said frame and provided with a housing, a recessed protuberance, a shouldered stud, a bearing 95 for the multiplying-gear, said recessed protuberance forming a bearing for the front end of the spool, said housing and protuberance cut away to permit of the setting and operation of the multiplying-gear, a cap inclosing said plate and provided with an opening 100 adapted to receive the end of said stud to prevent the movement of the plate, means mounted upon said protuberance for connecting said cap to the frame, and means carried 105 by the cap and engaging in the frame for preventing the movement of the cap when the latter is secured to the frame.

15. In a fishing-reel, the combination with a reel-frame, a reel-spool and a multiplying-gear, of a head-plate secured therein and provided on its outer face with a bearing for the multiplying-gear, a housing, and a recessed protuberance carried by the housing, said protuberance forming a bearing for one end of the spool. 110

16. In a fishing-reel, the combination with a reel-frame, a reel-spool and a multiplying-gear, of a head-plate secured therein and provided on its outer face with a bearing for the multiplying-gear, a housing, a recessed protuberance carried by the housing, said protuberance forming a bearing for one end of the spool, and means engaging in the other end of the frame for forming a bearing for the other end of the spool. 115

17. In a fishing-reel, the combination with a reel-spool and a multiplying-gear, of a reel-frame provided with a front and rear end band, each of which is interiorly screw-threaded, a 120

125

130

head-plate mounted in said front band and provided with a housing carrying a recessed protuberance which forms a bearing for one end of the spool, said plate further carrying a bearing for the multiplying-gear, means engaging with the screw-threads of the front band for fixedly securing said plate in position, and means forming a bearing for the other end of the spool, said bearing forming means engaging the threads of the rear band.

18. In a fishing-reel, the combination with a reel-spool and a multiplying-gear, of a reel-frame provided with a front and rear end band, each of which is interiorly screw-threaded, a head-plate mounted in said front band and provided with a housing carrying a recessed protuberance which forms a bearing for one end of the spool, said plate further carrying a bearing for the multiplying-gear, means engaging with the screw-threads of the front band for fixedly securing said plate in position, means forming bearings for the other end of the spool, said bearing forming means engaging the threads of the rear band, a cap mounted upon the front band, and means mounted upon said protuberance for securing said cap to the frame.

19. In a fishing-reel, the combination with a

reel-spool and a multiplying-gear, of a reel-frame provided with a front and rear end band, 30 each of which is interiorly screw-threaded, a head-plate mounted in said front band and provided with a housing carrying a recessed protuberance which forms a bearing for one end of the spool, said plate further carrying a bearing for the multiplying-gear, means engaging with the screw-threads of the front band for fixedly securing said plate in position, means forming a bearing for the other end of the spool, said bearing forming means engaging 40 the threads of the rear band, a cap mounted upon the front band, means mounted upon said protuberance for securing said cap to the frame, means carried by said cap and engaging in said frame to prevent the movement of 45 the cap when the latter is secured to the frame, and means carried by the plate and engaging in the cap to prevent the rotation of the plate when secured in the frame.

In testimony whereof I have hereunto set my 50 hand in presence of two subscribing witnesses.

WILLIAM CARTER.
